(57) **CLAIM**

The ornamental design for an eyeglass lens, as shown and described.

DESCRIPTION

FIG. 1 is a top front perspective view of a first embodiment of an eyeglass lens according to our new design;

FIG. 2 is a bottom rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the portion of the eyeglass lens in FIGS. 1-8 identified as Detail 9 in FIG. 1;

FIG. 10 is an enlarged view of the portion of the eyeglass lens in FIGS. 1-9 identified as Detail 10 in FIG. 2;

FIG. 11 is a top front perspective view of a second embodiment of an eyeglass lens according to our new design;

FIG. 12 is a bottom rear perspective view thereof;

FIG. 13 is a front elevation view thereof;

FIG. 14 is a rear elevation view thereof;

FIG. 15 is a left side elevation view thereof;

FIG. 16 is a right side elevation view thereof;

FIG. 17 is a top plan view thereof;

FIG. 18 is a bottom plan view thereof;

FIG. 19 is an enlarged view of the portion of the eyeglass lens in FIGS. 11-18 identified as Detail 19 in FIG. 11; and, FIG. 20 is an enlarged view of the portion of the eyeglass lens in FIGS. 11-19 identified as Detail 20 in FIG. 12.

Dashed lines in the drawings illustrate portions of the eyeglass lens that form no part of the claimed design. Long-dash, short-dash, short-dash broken lines indicate cut-off boundaries for enlarged detail views and form no part of the claimed design. Stippling shown in the drawings represents a contrast in appearance.
